UNITED STATES PATENT OFFICE.

WILLIAM WELSHAUSEN, OF ALLENHURST, NEW JERSEY.

HEATING DEVICE FOR AUTOMOBILE-ENGINES.

1,250,059.

Specification of Letters Patent. Patented Dec. 11, 1917.

Application filed May 6, 1916. Serial No. 95,828.

To all whom it may concern:

Be it known that I, WILLIAM WELSHAUSEN, a citizen of the United States, residing at Allenhurst, in the county of Monmouth and State of New Jersey, have invented certain new and useful Improvements in Heating Devices for Automobile-Engines, of which the following is a specification.

This invention has as its object to provide a device for maintaining a circulation of hot water through the radiator and water jacket of an automobile engine so as to prevent freezing of the water when the automobile is left standing in the cold or is left standing in an unheated garage.

It is one aim of the invention to so construct the device that the same may be readily placed in operation and the use thereof readily discontinued prior to cranking of the engine.

Another aim of the invention is to provide a device of the class mentioned which may be manufactured at a low cost and which will be economical in the consumption of fuel.

Another aim of the invention is to provide a novel construction of heater especially adapted for use in a heating system of this class.

30 In the accompanying drawings:

Figure 1 is a side elevation of the device mounted within the hood of an automobile.

Fig. 2 is a detail vertical sectional view through the heater.

35 Fig. 3 is a horizontal sectional view on the line 3—3 of Fig. 2.

Fig. 4 is a detail fragmentary perspective view of the valve for controlling the flow of liquid fuel to the heater and the float 40 for actuating the said valve.

In the drawings and more particularly in Fig. 1 thereof, the engine of the automobile is indicated by the numeral 1 and the radiator by the numeral 2, the water jacket 45 for the engine being indicated at 3. The numeral 4 indicates a water pipe which is connected as at 5 to the water jacket 3 near the bottom thereof and at its other end this pipe is connected to the radiator 2 at the

50 bottom of the said radiator. A pipe 6 leads from the upper portion of the radiator 2 and is enlarged and communicates with the top of the water jacket 3 as indicated at 7. At this point it will be understood that 55 water heated within the pipe 4 will ascend into the radiator 2 and will flow from the

radiator back to the water jacket 3 and thence again through the said pipe 4. In order to insure of flow of water along the course stated, the pipe 4 is provided a suitable distance rearwardly of the point of its communication with the radiator 2 with a downward bend 8 and from this bend is inclined upwardly to its said point of communication with the radiator as indicated 60 by the numeral 9. The heater proper which will now be described, is so located that the flame therefrom will play upon the pipe 4 at a point immediately in advance of the bend 8 and it will be understood that due 65 to the provision of this bend and the upward inclination of the pipe from the said bend toward its point of communication with the radiator 2, the water heated within the pipe will flow toward the forward end 70 thereof or, in other words, toward the said radiator and will not have a tendency to flow back past the bend 8.

The heater proper comprises a hollow oil reservoir or font 10 provided with a cover 11 removably secured in place as for example by screws 12. At one side the font 10 is provided with an attaching bracket 13 adapted to be secured to any convenient part of the automobile so as to position the 80 heater beneath the portion 9 of the pipe 4. The cover 11 of the heater carries a burner 14 and the cover is further provided with a wick tube 15 the lower end of which surrounds the upper end of a wick tube 16 90 which extends upwardly within the font 10 centrally thereof, a wick 17 of the tubular type being slidably received between the said wick tubes. The burner 14 is provided with the usual stem 18 for raising and lowering the wick as in the case of the ordinary oil lamp. In its bottom the font 10 is provided with a drain valve 19 which may be opened to permit of drawing off of the liquid fuel within the font and any sediment which might accumulate in the bottom 100 of the font.

In order that the font may be supplied with liquid fuel and that the supply to the font may be controlled by the driver of the machine, a liquid fuel reservoir 20 is mounted upon the dashboard of the vehicle and a pipe 21 leads from this reservoir and is connected as at 22 to the lower end of a valve casing 23 either formed integrally upon or secured upon the rear side of the font 10. The pipe 21 discharges into a passage 24

- formed in the lower end of the casing 23 and this passage at its inner end communicates by way of a conical valve seat 25 with the interior of the said casing, which in turn 5 is in communication, as indicated at 26, with the interior of the font. The numeral 27 indicates a float which is preferably annular in form and which surrounds a tubular downward extension 28 of the cover 11 10 which extension in turn surrounds the wick tubes 15 and 16 as clearly shown in Fig. 2 of the drawings. The float 27 is provided at one side with a stem 29 which is pivotally mounted between its ends as at 30 within the 15 upper portion of the casing 23, the float being located at one side of the pivot 30 and the said stem being provided at the other side of the pivot with an opening 31 loosely receiving the stem 32 of a needle valve 33 20 which needle valve normally occupies the seat 25 but is adapted upon fall of the float 27, to be lifted from the said seat whereby to permit liquid fuel to flow from the pipe 21 in to the font 10. The lift of the needle valve may be varied by adjusting a nut 34 which is threaded onto the upper end of the valve stem 32 and coacts with the upper side 25 of the stem 29 at the upper end of the opening 31. 30 From the foregoing description of the invention it will be understood that when the automobile is to be left standing in the cold or is to be left in an unheated garage, the oil heater herein described may be placed in 35 operation and the heat from the flame will heat the water in the pipe 9, causing the heated water to rise into the radiator 2 and thence flow through the pipe 6 to the water jacket 3 and back again into the first men- tioned pipe. As the liquid fuel is consumed 40 the level thereof within the font will fall and with it the float 27, resulting in the needle valve being lifted from its seat so as to permit of the flow to the font of more of the liquid fuel. Therefore, the device is 45 entirely automatic in its action and may be left over night without further attention on the part of the owner of the machine. 50 In order that access may be had to the interior of the valve casing 23 for the purpose 55 of adjusting the nut 34, the upper end of the said casing is preferably closed by a screw cap 35. 55 At the lower end of the portion 9 of the pipe 4, the pipe is provided with a water chamber 8' which serves the purpose of a boiler in which the water may be heated before circulating through the system. 60 Having thus described the invention, what is claimed as new is: 65
- In a liquid fuel burner of the class described, a font, a wick tube extending downwardly into the font, a float arranged within the font and surrounding the wick tube, a stem at one side of the float pivotally mounted within the font at one side thereof, the font at its said side having an inlet provided with a valve seat, a valve disposed to normally rest by gravity upon the seat and having an upstanding stem, a collar carried by the stem of the float at the other side of the said pivot and loosely surrounding the stem of the valve, the said valve stem being threaded, and a nut adjustably fitted upon the said valve stem and constituting an abutment for the said collar. 70 75
- In testimony whereof I affix my signature.
- WILLIAM WELSHAUSEN. [L. S.]
